UNITED STATES PATENT OFFICE

153,993

DESIGN FOR AN IRON HOLDER

Chester D. Stanley, Akron, Ohio

Application September 18, 1947, Serial No. 141,463

Term of patent 14 years

(Cl. D49—6)

To all whom it may concern:

Be it known that I, Chester D. Stanley, a citizen of the United States, residing at Akron, in the county of Summit and State of Ohio, have invented a new, original, and ornamental Design for an Iron Holder, of which the following is a specification, reference being had to the accompanying drawing, forming part thereof.

In the drawing:

Fig. 1 is a front elevational view of an iron holder showing my new design,

Fig. 2 is a side elevation thereof, and

Fig. 3 is a top plan view of Fig. 1.

I claim:

The ornamental design for an iron holder, substantially as shown.

CHESTER D. STANLEY.
